(57) **CLAIM**

The ornamental design for a rotary power tool, as shown and described.

DESCRIPTION

FIG. 1 is a front elevational view of the rotary power tool showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a front perspective view thereof;
FIG. 8 is a rear perspective view thereof;
FIG. 9 is a perspective view thereof with a first tool bit;
FIG. 10 is a perspective view thereof with a second tool bit;
FIG. 11 is a perspective view thereof with a third tool bit;
FIG. 12 is a perspective view thereof with a fourth tool bit;
and,
FIG. 13 is a perspective view thereof with a fifth tool bit.
The broken lines showing the first to fifth tool bits are for the purpose of illustrating the environmental structure and form no part of the claimed design.
